CONTACT BRIDGE FOR INTERCEPT BLOCKS

Application filed August 17, 1931. Serial No. 557,538.

This invention relates to known central station wiring equipment for dial telephones and pertains more particularly to auxiliary means for facilitating the operation of the 5 intercept block on the intermediate distributing frame.

The primary object of our invention is to provide a simple and effective clip appliance which the attendant can quickly apply to the 10 intercept block and thereby intercept a telephone that is ordered to be discontinued and establish communication between any party who calls such telephone and the central station intercept operator.

15 Heretofore it has been necessary for the attendants to make such change-overs by soldering and unsoldering the ends of at least three short jump wires to the appropriate six lugs or terminals on the intercept blocks.

20 Our invention eliminates this labor and expense and saves time.

For the purpose of leading up to a correct comprehension of the problem that has been solved by the present invention, reference 25 may be had to the accompanying drawings.

Fig. 1 diagrammatically shows the lines and connections of a dial telephone system to which our improvement is adapted to be applied.

30 Fig. 2 is an enlarged isometric view of the intercept block showing our improvement applied to the terminal lugs.

Fig. 3 is a side view of one of the conductive elements of the clip.

35 Fig. 4 is a side view of an intercept block, partly broken away, some of the connecting wires having been detached from the terminal lugs to permit the clip to be applied thereto.

40 Fig. 5 is a front view of the same, broken away in part.

Fig. 6 shows a modified form of clip application.

45 As is known, the function of the intercept block on the intermediate distributing frame is to intercept all calls that may be directed to a telephone that has been discontinued or temporarily disconnected and to deliver them to the ear of an intercept operator who thereupon explains to the calling party that the

called subscriber's telephone has been disconnected.

We will first describe the pertinent features of operation of a known dial telephone system to which our invention is adapted to 55 be applied.

The intercept block is a part of the intermediate distributing frame equipment. It usually consists of a base plate 1 of insulating material, called the terminal strip, and a 60

group of about one hundred twenty flat terminal lugs 2 that are permanently fixed to the terminal strip 1 and project through it equally on opposite sides. A typical intercept block, Figs. 2, 4, 5, has its lugs arranged in 65 parallel rows that extend from the front edge of the strip toward its back edge, there being six lugs to each row, corresponding to one telephone number. The individual lugs have their flat faces in the plane of the row.

Each row comprises two sets of lugs, those of the first set connected to the line, those of the other set connected to the intercept operator. As many rows of lugs as desired, 70 usually twenty, may be mounted side by side 75

on the terminal strip. Of the six lugs in each row the lower ends of the first set, *a*, *b*, *c*, are connected respectively to three wires 3, 4, 5 leading to the connector terminal shown in 80

Fig. 1, and their upper ends are soldered to three wires 7, 8, 9 leading to the line finder block 10. Each subscriber's telephone is connected by two wires 11, 12 to the main distributing frame and thence by a two-wire 85

cable 13 to two lugs *b*, *c*, of the first set of lugs just described. The remaining set of lugs *d*, *e*, *f* of each row are connected to set of trunk lines 14, 15, 16 that lead to the intercept flash signal 17 and to the telephone 18 90

of the central station intercept operator.

During the ordinary operation of the dial telephone system the last mentioned set of lugs *d*, *e*, *f* are not connected to the subscriber's lines and consequently the intercept operator performs no function. When a subscriber's telephone is to be disconnected the two lines 11, 12 leading from the subscriber's telephone to the main distributing frame are disconnected, as shown in Fig. 1, and the three wires leading from the upper ends of 100

the first set of lugs *a*, *b*, *c* to the line finder block 10 are disconnected by unsoldering them from the lugs. In their stead the ends of three short jump wires 19, 20, 21 must be 5 soldered to the upper ends of the first set of lugs *a*, *b*, *c* and the other ends of the jump wires must be soldered respectively to the last mentioned set of lugs *d*, *e*, *f* communicating with the intercept operator's telephone 18. Thereafter, all calls directed to the disconnected subscriber's telephone are shunted automatically to the intercept operator who informs the calling party that the 10 number he seeks has been disconnected. All 15 unused numbers, including those held in reserve for future growth of the system, are jump wired in that way on the intercept block of the intermediate distributing frame so that any call erroneously directed to a 20 number for which there is no subscriber is likewise shunted automatically to the intercept operator.

When a telephone heretofore disconnected is ordered into service again its three jump 25 wires 19, 20, 21 must be unsoldered from the six lugs *a*—*f* comprising the appropriate row on the intercept block of the intermediate distributing frame in order to eliminate the intercept operator from the subscriber's circuit. Then the upper ends of the 30 first set of lugs *a*, *b*, *c* in the row must be resoldered to the three wires 7, 8, 9 that lead to the line finder block, and finally the two 35 previously disconnected wires 11, 12 leading to the main distributing frame are resoldered so that out-going calls can be transmitted from the newly connected telephone.

The stated object of our invention is to 40 provide a simple inexpensive means that can be used to easily and quickly shunt a disconnected subscriber's telephone at the intermediate distributing frame block to the intercept operator, dispensing with the three jump wires and avoiding the cost of labor 45 and material heretofore necessitated by soldering and unsoldering the six wire connections of the lugs of a row.

We accomplish this result by providing a 50 conduit bar 22, preferably built up of three superimposed flat strips or laminæ 23, 24, 25 of conductive sheet metal and four laminæ 26, 27, 28, 29 of non-conductive sheet material, preferably fibre, all the laminæ being bolted, riveted or molded together in such 55 manner that the conductive strips 23, 24, 25 are electrically insulated from each other. Two contact elements in the form of spring clips, as 25*a* and 25*b*, are formed on each conductive strip, as 25. The clips of one 60 strip are arranged so as to register with the first and fourth lugs *a*, *d* of the intercept block on the intermediate distributing frame and the clips of the other two conductive elements are positioned to register with the second and fifth and third and sixth lugs re-

spectively. Each clip is preferably formed so as to yieldingly contact with the corresponding lug, and all six clips are arranged on the laminated conduit bar 22 so they will be applied simultaneously to all six lugs of a row when the attendant slips the bar into the way 30 defined by two rows of lugs. 70

Preferably the clips are shaped so as to project upwardly from the upper edge of the bar and are folded downwardly upon themselves so as to present inverted hook-shaped springs whose lower free ends 25*a'*, 25*b'* are yieldingly opposed to an insulated face 26 of the bar. When the bar is slipped in between two rows of lugs and its six spring hooks embrace the upper ends of the six lugs comprising one of the rows, the attendant merely pushes the bar downward and thus seats it on the insulated terminal strip 1. The hooks slide downward on the lugs and establish adequate electrical communication between the opposite sets of lugs in alternating pairs *a*, *d*—*b*, *e*—*c*, *f*—, *a* and *f* being the outer lugs of each set and *c* and *d* the inner lugs. Thereafter all calls directed through that row of lugs will be transferred automatically to the receiver of the intercept operator. Thus the three jump wires are rendered unnecessary and no soldering and resoldering of jump wire connections is required. 80 85 90 95

In Fig. 1 at the left of the intermediate distributing frame is shown diagrammatically a bar 22 of our invention, in order to indicate its operative relationship to the lugs *a*, *b*, *c*, *d*, *e*, *f* when the bar 22 is used instead of the ordinary soldered jump wires 19, 20, 21. 100

A modified form of our clip appliance is illustrated in Fig. 6, the conduit bar comprising a single strip of insulated material 31 formed with three longitudinally disposed slots to receive three flat strips of conductive material 32, 33 and 34. Each strip is insulated from the others and provided with two outwardly and upwardly curved spring prongs 35. When this conduit bar is pushed down between two rows of terminal lugs the free ends of the curved spring prongs 35 contact resiliently with the flat faces of six terminals of a row, the back face of the insulated strip 31 bearing against the opposing row of terminal lugs. 110 115 120

A supply of clips is kept at hand and the attendant applies them to the intercept block or removes them according to his orders for connecting or disconnecting service telephones. 125

All incoming calls for a discontinued telephone number or for a number that has not yet been put into service will automatically go to the intercept operator so long as the appropriate row of lugs is engaged by a clip. When a clip is not occupying a row of lugs the intercept operator is kept from automatic 130

communication with the subscriber's line corresponding to that row.

We have referred to the visible signal 17 and the audible signal or telephone 18 as instruments that are located at the station of the intercept operator, but in lieu of those signals a loud speaker or other annunciating or alarm device may be employed in case it is desired to sound an emergency alarm or 10 notify attendants at the central station that the discontinued subscriber's number has been called. For instance, it would be possible with this device for the proper authority to temporarily cut out a subscriber's telephone and if a call for that number is thereafter received the alarm is sounded in the telephone exchange or in the office of a proper official. The ability of this apparatus to be applied to a terminal block so as to almost 20 instantly cut out a telephone and thereafter produce a signal if the number is called is one of its advantageous features.

Having thus described our invention, what we claim and desire to secure by Letters Patent is:

1. In a dial telephone system having an intercept block including terminal intercept lugs and line lugs arranged in a plurality of parallel rows, each row having two sets of 30 three lugs each connected respectively to the intercept operator and to the line, means for establishing electrical communication between two sets in a row comprising, a conduit bar adapted to be removably inserted between two rows of lugs, said bar including three strips of conductive material separated by thin layers of non conductive material, two contact elements formed on each strip and projecting laterally away from the bar, 35 said elements of each strip arranged to engage respectively an intercept lug and a line lug in such manner that each lug of a set is electrically connected to the appropriate lug of the other set in the same row.

45 2. In a dial telephone system having an intercept block including terminal lugs arranged in a plurality of rows, each row comprising two sets of lugs connected respectively to the intercept operator and to the line, 50 means for establishing electrical communication between said two sets of any desired row, comprising a conduit bar adapted to be removably inserted between two rows of lugs, said bar including a plurality of superimposed conductive strips insulated from each other, two contact elements formed at 55 the marginal edge of each conductive strip, spaced apart and shaped to present spring clips, said contact elements of each strip 60 being disposed so that each yieldingly engages an appropriate lug of each set.

3. In a dial telephone system having an intercept block including terminal lugs arranged in rows, each row comprising two 65 sets of lugs connected respectively to the in-

tercept operator and to the line, means for establishing electrical communication between the two sets of a row, comprising, a conduit bar adapted to be removably inserted and wedged between two rows of lugs, said 70 bar including a plurality of superimposed conductive strips insulated from each other, two contact elements formed at the marginal edge of each strip, spaced apart and projecting laterally away from the bar, said contact 75 elements of each strip being so disposed as to engage an appropriate lug of each set.

4. In a dial telephone system having an intercept block including terminal lugs arranged in rows, each row having two sets of 80 lugs connected respectively to the intercept operator and to the line, means for establishing electrical communication between two sets in a row comprising, a member adapted to be removably inserted between two rows of lugs, said member including a plurality of superimposed conductive strips insulated from each other, two exposed contact elements formed on each strip and spaced apart, said elements of each strip being so disposed as to engage the flat face of a lug 85 of each set.

In testimony whereof, we affix our signatures.
